UNITED STATES PATENT OFFICE

108,062

DESIGN FOR ELASTIC FABRIC OR SIMILAR ARTICLE

Harry Aull, Philadelphia, Pa., assignor to Friedberger-Aaron Manufacturing Company, Philadelphia, Pa., a corporation of Pennsylvania

Application October 13, 1936, Serial No. 65,283

Term of patent 7 years

To all whom it may concern:

Be it known that I, Harry Aull, a citizen of the United States, residing in Philadelphia, county of Philadelphia, State of Pennsylvania, have invented a new, original, and ornamental Design for Elastic Fabric or Similar Article, of which the following is a specification, reference being had to the accompanying drawing, which forms a part thereof.

In the drawing, Figure 1 is a plan view of an elastic fabric embodying my design, shown in

unstretched condition. The figure shows the fabric about actual size.

Figure 2 is a plan view of the same elastic fabric stretched longitudinally to the extent incident to normal use. This figure also shows the fabric about actual size.

I claim:

The ornamental design for elastic fabric or similar article as shown and described.

HARRY AULL.
